FIG. 3

FIG. 4

FIG. 5

FIG. 1 is a top plan view of a fishing tackle box or similar article, showing my new design in open position, a portion of the cover of the central inner compartment being broken away and omitted to show the appearance of the interior thereof;

FIG. 2 is a front elevational view in open position, partly in cross-section where the cover was broken away in FIG. 1;

FIG. 3 is a rear elevational view in closed position;

FIG. 4 is a bottom plan view, in closed position;

FIG. 5 is a front elevational view, in closed position;

FIG. 6 is a top plan view, in closed position;

FIG. 7 is a left end elevational view, in closed position;

FIG. 8 is a right end elevational view, in closed position; and

FIG. 9 is a left end elevational view thereof, in open position.

I claim:

The ornamental design for a fishing tackle box or similar article, substantially as shown.
